BOX

Brock F. Brockway, Mill Valley, Calif., assignor to
E. D. Bullard Company, Sausalito, Calif.

Filed Feb. 16, 1966, Ser. No. 1,074

Term of patent 14 years

(Cl. D58—12.6)

FIG. 6

FIG. 7

FIG. 8

FIG. 9

FIG. 1 is a top view of a box showing my new design;
 FIG. 2 is a front elevational view thereof;
 FIG. 3 is a rear elevational view thereof;
 FIG. 4 is a side view taken from the right side of FIG.
 3, the opposite side being a mirror image;
 FIG. 5 is a bottom view;
 FIG. 6 is a top plan view thereof in open condition;
 FIG. 7 is a side elevational view of FIG. 6;
 FIG. 8 is a cross-sectional view taken along line 8-8
 of FIG. 6; and
 FIG. 9 is a cross-sectional view taken along line 9-9
 of FIG. 6.
 I claim:
 The ornamental design for a box, as shown.
